UNITED STATES PATENT OFFICE

152,021

DESIGN FOR A PHOTOGRAPHIC CAMERA

Jean O. Reinecke, Oak Park, Ill., assignor to Bell & Howell Company, Chicago, Ill., a corporation of Illinois

Application January 20, 1948, Serial No. 143,917

Term of patent 14 years

(Cl. D61—1)

To all whom it may concern:

Be it known that I, Jean O. Reinecke, a citizen of the United States, residing at Oak Park, in the county of Cook and State of Illinois, have invented a new, original, and ornamental Design for a Photographic Camera, of which the following is a specification, reference being had to the accompanying drawing, forming a part thereof.

In the said drawing—

Figure 1 is a front elevation of a photographic camera, embodying my new design;

Figure 2 is side elevation of the same;

Figure 3 is a rear elevation of the same; and

Figure 4 is a side elevation of the same taken oppositely with respect to Figure 2.

The essential features of my design reside in the parts shown in full lines.

I claim:

The ornamental design for a photographic camera, as shown and described.

JEAN O. REINECKE.
